UNITED STATES PATENT OFFICE.

WALTER I. OESCHGER, OF DETROIT, MICHIGAN.

GASOLENE-GAGE.

1,172,481.

Specification of Letters Patent. Patented Feb. 22, 1916.

Application filed August 7, 1915. Serial No. 44,348.

To all whom it may concern:

Be it known that I, WALTER I. OESCHGER, a citizen of the United States of America, residing at Detroit, in the county of Wayne 5 and State of Michigan, have invented certain new and useful Improvements in Gasolene-Gages, of which the following is a specification, reference being had therein to the accompanying drawings.

10 This invention relates to a gasolene gage, and more particularly to that type designed for gasolene tanks or receptacles and adapted to indicate the quantity or level of gasolene within the tank or receptacle, such 15 gages having been used in connection with the main gasolene supply tank of automobiles and similar vehicles.

My invention aims to furnish the filling opening of a gasolene tank or reservoir with 20 a plug having a gage that is removable with the plug, thus necessitating an actuating mechanism for the gage which can readily pass through the filling opening of the tank or reservoir, but in making the actuating 25 mechanism of such size, provision is made to increase the action of the mechanism and thereby obtain as great a sensitiveness for perfect reading upon the gage as though the actuating mechanism was of such size as to 30 prohibit its ready removal from the gasolene tank or reservoir.

My invention further aims to provide a float actuated indicator for gasolene tanks or reservoirs wherein the parts are constructed with a view of reducing the cost of manufacture and at the same time retain the features, by which accuracy, durability and ease of assembling are secured, and with such ends in view, the invention resides in 40 the novel construction, combination and arrangement of parts to be hereinafter specifically described and then claimed.

Reference will now be had to the drawing, wherein—

45 Figure 1 is an elevation of a gasolene tank or reservoir, partly broken away, showing the gasolene gage in elevation; Fig. 2 is a vertical sectional view of the gasolene gage, partly broken away and partly in section; 50 Fig. 3 is an elevation of the inner end of the gage, and Fig. 4 is a plan of the gage partly broken away.

As illustrating a preferred embodiment 55 of my invention there is shown a gasolene tank or reservoir, 1, as having a filling opening 2 with the marginal edges of the open-

ing reinforced by a collar 3. The collar 3 is suitably secured to the tank or reservoir 1 and said collar is interiorly screwthreaded to accommodate a hollow plug 4. The outer 60 end of said plug has a peripheral flange 5 adapted to seat upon the collar 3, and the inner end of said plug has an inwardly projecting annular flange 6. Besides these flanges, there are vents or air openings 7 65 adapted to facilitate the flow of gasolene from the tank 1.

Seated upon the flange 6 within the plug 4 is an annular cage 8 provided with a bail or handle 9. Mounted in the annular cage 8 against an inwardly projecting flange 10 supporting the bail or handle 9 is a transparent plate 11 retained in engagement with said flange by a ring 12. The transparent plate 11 is preferably made of glass and below said plate against the ring 12, is a dial plate 13 circumferentially graduated, as shown in Fig. 4, with such designations as will indicate gallons or quantities of gasolene within the tank or reservoir 1. The dial 80 plate 13 is held against the retaining ring 12 by a closure plate 14 supported by inwardly projecting pins 15, carried by the cage 8.

The closure plate 14 has a central counter-sunk portion 15 and riveted or otherwise connected thereto, as at 17, is a depending stirrup or bracket 18. This bracket is composed of two parallel arms having the lower ends thereof enlarged, as at 19, and connected by spacing members 20 and 21, the latter serving as a bearing or guide for a vertical shaft 22, which has the upper end thereof journaled in the closure plate 14 and the dial plate 13.

95 Mounted upon the upper end of the shaft 22, between the transparent plate 11 and the dial plate 13, is a hand or pointer 23, and mounted upon the lower end of said shaft is a small beveled gear wheel 24 meshing with a large gear wheel 25, carried by a rock shaft 26 having reduced ends 27 thereof supported in the enlarged portions 19 of the bracket or stirrup 18.

Suitably connected to the rock shaft 26 105 is a float arm 28 and the outer end of said arm has a hollow spherical body or float 29 which is buoyant upon gasoline or other liquid fuel within the tank or reservoir 1.

To retain the cage 8 in the plug 4, a retaining ring or nut 30 is employed, said ring or nut being screwed in the outer end of the

2
plug through the medium of winged finger pieces 31 forming part of said ring or nut. The screw threads of the retaining ring or nut 30 may be right hand threads and the screw threads of the nut 4 may be left hand threads, whereby the winged finger pieces 31 can be used for removing the plug 4 from the collar 3 when it is desired to fill the tank or reservoir 1.

19 With the plug mounted in the collar 3, the bracket or stirrup 18 is rigidly held and the buoyant body or float 29 can remain upon the surface of a quantity or body of gasoline within the tank or reservoir. The 15 movement of the buoyant body or float 29 is limited by the arm 28 contacting with the spacing members 20 and 21, and when in engagement with the former, the gage in its entirety can be removed from the tank or 20 reservoir.

25 The cage 8 and its appurtenant parts is a bench assembled proposition that can be easily and quickly mounted in the plug 4, and the transmission mechanism between the rock shaft 26 and the indicator shaft 22 is such as to insure a correct reading upon the dial plate 13 and indicate to an observer the quantity of gasoline within the tank or reservoir, thus allowing the supply to be replenished before completely consumed.

What I claim is:—

1. A gasoline gage comprising a plug adapted for closing a gasoline tank, a detachable indicator housed in said plug and provided with a transverse handle to facilitate its removal, a nut holding said cage in said plug, a bracket supported by said indicator independent of said plug, a rock shaft carried by said bracket, a float connected to said rock shaft and adapted to impart movement to said rock shaft, and means in said bracket moved by said rock shaft and adapted to actuate said indicator.

2. A gasoline gage comprising a plug adapted as the sole closure of a gasoline tank, a detachable cage seated in said plug and provided with a handle to facilitate its removal, a nut holding said cage in said plug, a closure plate for said cage, a dial plate on said closure plate, a pointer above 45 said dial plate, and means carried by said closure plate independent of said plug and adapted to move said pointer.

In testimony whereof I affix my signature in presence of two witnesses.

WALTER I. OESCHGER.
